UNITED STATES PATENT OFFICE.

RIDSDALE ELLIS, OF OAK PARK, ILLINOIS, ASSIGNOR TO PAUL CARPENTER, OF GLENVIEW, ILLINOIS.

HEATER FOR COOLING SYSTEMS.

1,345,923.

Specification of Letters Patent.

Patented July 6, 1920.

Application filed January 25, 1917, Serial No. 144,424. Renewed October 31, 1919. Serial No. 334,883.

To all whom it may concern:

Be it known that I, RIDSDALE ELLIS, a subject of the King of Great Britain and Ireland, and a resident of Oak Park, in the county of Cook and State of Illinois, have invented certain new and useful Improvements in Heaters for Cooling Systems, of which the following is a specification.

This invention relates in general to improvements in warming means for water cooling systems and is particularly useful in connection with internal combustion engines having water cooling systems including water-jacket and radiator elements. Trouble frequently arises when automobiles having water-cooled engines are allowed to stand in unheated garages or at the curb in very cold weather owing to the gradual cooling of the water in the radiator or water-jacket, and the subsequent freezing thereof. Apart from the possible freezing of the water another trouble arises from the excessive cooling of the engine, namely, difficulty in starting the engine owing to difficulty in vaporizing the gasoline and maintaining it in the vaporized state.

The principal objects of my present invention are to provide improved means for preventing the water in a cooling system from freezing; to provide means whereby the normal thermal flow of water from the water jacket to the radiator and back is maintained after the engine has stopped running; to provide means for adjusting the amount of heat supplied to the cooling system of the engine according to the temperature of the water in the system; to provide means for preventing the temperature of the water in the engine water-jacket falling below a constant minimum temperature after the engine has stopped running; to provide means for heating the liquid fuel supplied on starting the engine; to provide means for heating the air supplied on starting the engine; and to provide means for supplying heat to the water, liquid fuel and air independently or simultaneously by energy, which may previously have been taken from the engine while running.

In attaining these and other objects and

advantages to be hereinafter set forth I have provided a construction one embodiment of which is illustrated in the accompanying drawings in which:

Figure 1 is a side view of the engine and associated parts of an automobile to which my improvements have been applied; and

Fig. 2 is a vertical section through a carburetor constructed in accordance with my present invention.

Referring now to the drawings, 1 represents the water jacket of an automobile engine, 2 the radiator and 3 the bonnet or hood. Water from the water jacket 1 passes through the uptake 2^a, flexible connection 2^b and pipe 4 to the upper part of the radiator. Water leaves the radiator by the pipe 5 which is connected to the centrifugal pump 6 by means of flexible connection 8 and pipe 7. The water leaves the centrifugal pump by the pipe 9 to which the pipes 10 and 11 are connected by means of a T-joint.

In using an automobile in cold weather two things are desirable, first, that the water in the radiator and water jacket be kept from freezing, and second, that the carburetor and the parts associated therewith be warm enough to enable the engine to be started without an excessive amount of work.

In order to satisfy the first of these requirements, it is only necessary that the water be kept just above freezing. To satisfy the second requirement, however, the temperature of the carburetor should preferably not be lower than 50° F. Evidently it requires considerable more energy to maintain the temperature of the water in the water-jacket and the radiator at 50° F. instead of, say 34° F. On the other hand it requires relatively little energy to heat the air and liquid fuel admitted to the carburetor for a brief period while starting the engine. Consequently so far as energy consumption is concerned a satisfactory arrangement would be one in which the water would be just kept above freezing, while separate means are provided for heating the air and gasoline sufficiently on starting to secure a good mixture.

In order to satisfy these requirements as far as may be, I provide an electric heater for the water which is thermostatically thrown into operation whenever the temperature of the water approaches a predetermined value, which, in order to save power, may conveniently be just above freezing point.

In order to secure easy starting, I also provide electric heaters for either or preferably both the air and liquid fuel admitted to the carburetor. These heaters will be thrown into operation immediately prior to the starting of the engine. In this way a minimum consumption of energy is obtained. This conservation of energy is particularly important in connection with an electric heating system operated from the storage battery of a car for the reason that the amount of energy in the battery is never large and a relatively large quantity of electrical energy is needed to produce a relatively small heating effect on the water.

For heating the water I have provided an electric heater 12 connected at its lower end by the pipe 14 to the intake side of the pump 6, and at the upper end by pipe 15 to the lower rear corner of the water-jacket. The pipe 15 is connected to the lower rear corner of the jacket in order to give as complete a circulation of the water through the system as a whole as is possible. The current is passed through the electric heater 12 from the storage battery 16 of the car whenever the temperature of the water in the pipe 7 is low enough to operate the thermostatic switch or circuit closer 17. This thermostat is arranged in the pipe leading to the radiator through the pump as this is the coldest part of the whole water cooling system in order to insure that the thermostat will always operate before any part of the water-cooling system commences to freeze.

The carburetor shown in Fig. 2 is characterized by the provision of a heater 13 for the air and a heater 18 for the gasoline. The carburetor comprises a throttle 19, Venturi tube 20, jet 21, float chamber 22 and auxiliary air valve 23. The heater 13 is arranged between the lower part of the Venturi tube and the curved air inlet 24 which is normally attached directly to the lower part of the Venturi tube. This part 24 has been dropped in order to allow the heater to be spaced between it and the Venturi tube. No heater is provided for the extra air valve as on starting this air valve does not necessarily open.

The heater 13 consists of two annular disks 25 with a circular aperture in their center portions of a diameter equal to the greatest diameter of the Venturi tube. A bridge 26 is arranged across this aperture in order to support a core 27, the purpose of

which will be described below. Between these annular rings 25 a thin metal tube 28 is arranged, on the outside of which a resistance wire 29 is coiled. Outside of this resistance wire is arranged a lagging 30. As the tube 28 is of very thin metal heat from the resistance coil will pass readily therethrough, while the lagging 30 prevents heat being radiated or conducted away into the surrounding atmosphere. One purpose of the core 27 (preferably of non-heat-conducting material) is to cause the air to flow in proximity to the heating tube 28. Another function of the core 27 is to provide a strong, rigid connection between the annular rings 25 so that the tube 28 may be made very thin so as to pass heat readily therethrough without weakening the strength of the heater as a whole. The ends of the resistance wire are connected to terminals 31 at each end of the heater to which terminals connection is made from the storage battery 16 of the car, through a switch preferably arranged on the dash-board.

For heating the gasoline a heater 18 is provided of a similar construction to that of the heater 13 except that no core is provided. Terminals 32 (one not shown) are provided on each side of the heater 18 for connecting the latter to the battery 16. Preferably the heaters 13 and 18 are connected in parallel with the switch in series with both so that they are brought into and out of operation simultaneously.

The heater 12 for the water is preferably constructed in similar manner to the heater 13.

To conserve heat as far as possible means are provided for preventing flow of air through the radiator. For this purpose a spring roller curtain 33 is provided which may be drawn upwardly across the front of the radiator by a cord 34 passing over a pulley 35 and fastened by a cleat 36 on the dash-board.

Having thus described my invention and illustrated its use, what I claim as new and desire to secure by Letters Patent is:—

1. In a water-cooled internal combustion engine the combination of a water cooling system, a carburetor, means for heating the water after the engine has stopped running and means for heating the air admitted to the carburetor to aid the vaporization and reduce the condensation of liquid fuel on starting the engine.

2. In a water cooled internal combustion engine the combination of a water cooling system, a carburetor, means for heating the water after the engine has stopped running and means for heating the air admitted to the carburetor to a higher temperature than said water.

3. In a water cooling system the combina-

tion of a water jacket, a radiator, means for preventing flow of air through said radiator after the normal supply of heat has ceased and heating means for the water adapted to operate below a predetermined temperature of the water.

In testimony whereof I have hereunto

signed my name in the presence of the two subscribing witnesses.

RIDSDALE ELLIS.
